UNITED STATES PATENT OFFICE.

JACOB PETRY, OF PITTSBURGH, PENNSYLVANIA.

PATTERN FOR DENTAL PLATES.

1,274,322.

Specification of Letters Patent. Patented July 30, 1918.

Application filed November 8, 1915. Serial No. 60,351.

To all whom it may concern:

Be it known that I, JACOB PETRY, a citizen of the United States, and resident of Pittsburgh, in the county of Allegheny and 5 State of Pennsylvania, have invented a new and useful Improvement in Patterns for Dental Plates; and I do hereby declare the following to be a full, clear, and exact description thereof.

10 My invention relates to patterns for dental plates and is particularly concerned with a pattern for a plate having an undercut cavity or socket for the reception of a suction retainer such as that shown in my Patent 15 No. 1,005,296, dated the 10th day of October, 1911.

One of the main objects of my present invention is to insure in the finished plate, that the bottom of the socket which receives 20 the suction retainer shall be at all points equal distances from the upper face of the plate, not only along the rim of the overhanging lip which overlaps the edge of the suction retainer, but also throughout the entire 25 tire area of said socket, so that when the suction retainer is secured in position in this receiving socket of the plate, said retainer will conform exactly to the contours of the roof of the mouth when the plate is in position.

30 Different expedients have been resorted to heretofore for securing this uniformity in the bottom of this socket, but in every case the plate is originally distorted from its proper contour or becomes so when the suction retainer is secured to it. Or, if the bottom of the socket is not distorted, the lip or rim over-lying the edge of the suction retainer is frequently distorted in the effort to 40 remove the molding material from the socket of the molded plate.

In the practice of my invention, I construct the pattern out of plastic material, preferably wax, and in at least two layers. 45 With the plastic layers I employ pattern plates of pliable material for the formation of the pattern of the socket in the plastic material. From this plastic pattern a mold is formed in the manner hereinafter to be 50 described.

For the purpose of a clear understanding of the invention, the various steps in the method are graphically illustrated in the accompanying drawings in which Figure 1 is 55 a perspective view of a plaster cast of the

roof of the mouth. Fig. 2 is a transverse section thereof on the line 2—2. Fig. 3 is a view similar to Fig. 1, showing the first socket pattern plate in position. Fig. 4 is a transverse section on Fig. 3. Fig. 5 is a view 60 showing the first layer of plastic material molded to the cast around the socket pattern plate. Fig. 6 is a section on the line 6—6, Fig. 5. Fig. 7 shows the second socket pattern plate on the cast, Fig. 5. Fig. 8 65 is a transverse section on the line 8—8, Fig. 7. Fig. 9 is a perspective view of the first plastic pattern layer. Fig. 10 is a similar view of the second plastic pattern layer. Fig. 11 is a perspective view of the plastic 70 pattern assembled. Fig. 12 is a sectional view of the pattern. Fig. 13 shows the plastic pattern incased in a mold flask with a molding material surrounding the same. Fig. 14 is a view similar to Fig. 10 illustrating 75 the mold cavity left by the pattern. Fig. 15 is a plan view of one of the mold sections showing the arrangement of the pouring or blow holes. Figs. 16 and 17 are perspective and sectional views respectively 80 of the completed metal dental plate.

In the embodiment of the invention herein illustrated, the plaster cast 1 shown in Fig. 1 is given the contour of the roof of the mouth throughout the area 2 by the usual 85 method of taking such impression, and it is the object thereafter that the mold for the dental plate shall conform exactly to these contours in its finished form. Ordinarily, it is a simple matter to produce a pattern 90 for the dental plate from such plaster cast, but with a dental plate of the peculiar construction, having the peculiar form of suction retainer illustrated in my companion patent above referred to, it is necessary that 95 this suction retainer throughout its area shall follow accurately the contours of that surface of the dental plate which has been so shaped. It is necessary to form within the dental plate a cavity or socket to receive 100 the securing foundation portion of the suction retainer, and this socket must therefore be provided with an over-lying lip extending throughout the perimeter of the socket. The edge of this lip must remain of the exact 105 contour of the corresponding portion of the roof of the mouth, and the bottom of the socket must conform accurately to the shape of that portion of the roof of the mouth which overlies the socket, but ob- 110

viously, the bottom of the socket will be removed some little distance from the normal plane or planes of the upper face of the finished plate, in order to provide clearance 5 for the suction retaining member between the bottom of the socket and the roof of the mouth, and this clearance space must be of uniform depth throughout, so that the suction retainer may be held in close relation 10 to the roof of the mouth when the dental plate is in position.

One of the prime objects of this invention, therefore, is to produce a mold which will accurately form the dental plate throughout 15 the proper configuration, but especially one which will produce the bottom of the socket in such plate in exact conformity with that portion of the roof of the mouth which overlies the socket. Many expedients have 20 been tried, but none heretofore in my experience have been successful, for the reason that the over-hanging lip of the socket is almost invariably distorted when the pattern is filled in the mold flask, or when the 25 pattern is being removed therefrom, or finally, when the molded plate is removed from the pattern.

In order to overcome these difficulties, I form the pattern itself of two superposed 30 layers of material, in one of which the opening and outline of the socket lip is formed, and on the other the contours of the base of the socket. For accurate molding, I employ plastic material for the pattern and 35 for a purpose hereinafter described, I prefer to employ easily fusible material, such as wax. The members for forming the socket and opening in the pattern, over and around which the plastic material or wax may be 40 shaped, must be of pliable material, in order that they may conform exactly to the contours of the roof of the mouth overlying the socket opening, and overlying the overhanging lip of the socket.

45 Referring to the drawing, I first place upon the molded face of the plaster cast a thin plate 3, of pliable material, such as tin foil, tissue paper, or like material, which is pressed down hard against the molded face 50 to cause the same to conform exactly to its contours. A layer of plastic material which I shall hereafter refer to as wax is then placed over the molded face of the cast and over the plate 3, is firmly pressed down 55 around the plate 3, and finally is cut away over said plate, leaving a molded rim such as 4, Fig. 5, surrounding the plate and flush therewith, as indicated in Fig. 6, which completes the molded surface of the upper face 60 of the pattern, or that face which conforms exactly to the contours of the roof of the mouth, as determined by the plaster cast.

The opening formed in this first wax layer 4 conforms exactly to the shape of the suc-

tion retaining member, or so much thereof 65 as is to be exposed to the roof of the mouth. This suction retaining member, however, is fastened in place by means of a projecting lip or lateral extension of its base or foundation member and may be cemented thereto; 70 therefore, the socket in the dental plate must have an undercut cavity to receive this suction retainer fastening lip. In this is presented the problem which this invention 75 in the main is intended to solve.

Referring to Fig. 7, it will be seen that a second plate 5, symmetrical in outline with the plate 3, but of larger area, is placed upon said plate 3 and is pressed firmly down upon said plate, so that it will partake exactly of 80 the molded contour of this plate 3, which as before described, conforms to the contours of the molded face 2 of the plaster cast 1.

A second layer of wax such as 6, Fig. 8, is then molded over the plate 5 and over 85 the exposed rim 4 of the first wax layer. Thus it will be seen that portion of the wax layer 6 adjacent the face 7 of the plate 5, will form the bottom of the socket in the finished pattern, and this bottom face of the 90 socket will necessarily follow accurately the contours of the roof of the mouth throughout the area of the plaster cast underlying the plate 3. At the same time, the portion of the first wax layer 4 extending beneath 95 the edges of the plate 5 will form a lip 8 surrounding the suction retainer opening in the pattern and the space beneath the lip 8 forms the undercut cavity for the reception 100 of the projecting securing lip of the foundation or backing of the suction retainer.

Before placing the upper layer 6 of wax over the plate 5, and the wax layer 4, the exposed faces of the plate 3, and of the first wax layer 4, are given a thin coating of oil 105 or layer of tissue paper; tin foil or similar material is placed between the wax layers 4 and 6 and the plates 3 and 5, so that the parts may be readily separated for the removal of the shaping plates 3 and 5. Fig. 110 9 and Fig. 10 show these wax layers separated and the plates 3 and 5 removed. The two wax layers are then placed together again, and produce the complete pattern in wax that is shown in perspective face view, 115 Fig. 11, and in sectional view, Fig. 12, wherein the suction retaining cavity or socket is clearly apparent, said socket having the bottom 9 conforming exactly to the contours of the plaster cast 2, the retaining 120 rim 8 which also conforms exactly to the contour of the roof of the mouth, and forms the undercut portion 10 for the reception of the securing part of the suction retainer.

For the purpose of forming from this pattern the mold for the dental plate, the socket or the cavity is first filled with material in semi-fluid state, which completely 125

fills the cavity, including the undercut portion 10 and by reason of its fluid conditions, extends into the inmost recesses of said cavity. The use of a camel's-hair brush brush-
 5 ing the soft investment compound underneath the flange, and tapping mold may be advisable.

One half of the mold flask 11, Fig. 13, is filled to the proper depth with the molding material 12, and the pattern is laid upon this material and impressed into it. The other half 13 of the flask is also filled with the molding material 12 and filled in against the wax pattern and the filled portion of the
 10 cavity. The mold is then provided with the usual blow hole 14 and pouring hole 15, and the two sections are clamped together in the usual manner. The mold is then heated for the purpose, not only of drying out the mold
 15 material, but also melting out the wax pattern which is absorbed by the mold material, leaving the mold cavity entirely clear. This melting out of the wax has also the advantage that it fills up the pores of the
 20 mold material around the mold cavity, leaving a smooth, clean-cut surface for the production of the molded dental plate. The molten metal from which the plate is to be formed is then poured into the mold in the usual manner; the sections of the mold flask are then separated, and the molded dental plate 16 removed therefrom. All vestige of the molding material is then cut out or otherwise removed from the suction retain-
 25 ing cavity or socket 17 and particularly from the under cut cavity 18. It will be seen, therefore, that the molded face 19 of the plate will conform exactly to or will be a reproduction of the molded face 2 of the
 30 plaster cast 1, and the edge 20 of the lip 21 overlying the perimeter of the cavity or the socket, will likewise conform throughout, to the contours of the roof of the mouth. The cross section of the undercut cavity 18 of the
 35 socket, is exactly the same as that of the securing rim or lip of the suction retainer. The latter, therefore, may be inserted within this cavity, and secured in place in any de-
 40 sired manner, as by cement, and the suction
 45 retaining portion of the suction retainer will extend into the opening in the inner face of the plate, and by reason of the fact that the bottom 22 of this cavity corresponds throughout in contour with the contour of
 50 the opposite portion of the roof of the mouth, it is obvious that the suction retainer will be held in a shape likewise to conform. Hence, there will be no uncom-
 55 fortable or irritating projection of the suc-
 60 tion retainer above the inner face of the dental plate.

While I have herein described a particu-
 lar embodiment of the invention, and a particu-
 lar method of carrying the same into

effect, it is to be understood that the inven- 65
 tion may be altered in details and arrange-
 ment of parts, within the scope of the ap-
 pended claims.

What I claim is:

1. A molding pattern for articles having 70
 an undercut cavity therein, comprising a layer of more or less readily fusible ma-
 terial, having an opening therein conform-
 ing to the opening of the cavity, a second
 layer of similar material having a recess 75
 therein of an area equal to the greatest area
 of the cavity, said layers being superposed
 one upon the other.

2. A molding pattern for articles having 80
 an undercut cavity therein, comprising a 80
 layer of more or less readily fusible ma-
 terial, having an opening therein conform-
 ing to the opening of the cavity, a second
 layer of similar material having a recess 85
 therein of an area equal to the greatest area
 of the cavity, said layers being superposed
 one upon the other, and a coating of lubri-
 cating material between the layers.

3. A molding pattern for articles having 90
 an undercut cavity therein, comprising a 90
 layer of more or less readily fusible ma-
 terial, having an opening therein conform-
 ing to the opening of the cavity, a second
 layer of similar material having a recess 95
 therein of an area equal to the greatest area
 of the cavity, said layers being superposed
 one upon the other, the exposed face of the
 first layer being shaped to conform exactly
 to one face of the articles, the portion of
 the other layer forming the cavity shaped 100
 to parallel in all its contours a predeter-
 mined shape of the article which said ex-
 posed face of the first layer is intended to fit.

4. A molding pattern for articles having 105
 an undercut cavity therein, comprising a 105
 layer of more or less readily fusible ma-
 terial, having an opening therein conform-
 ing to the opening of the cavity, a second
 layer of similar material having a recess 110
 therein of an area equal to the greatest area
 of the cavity, said layers being superposed
 one upon the other, the exposed face of the
 first layer being shaped to conform exactly
 to one face of the article, the portion of
 the other layer forming the cavity shaped 110
 to parallel in all its contours, a predeter-
 mined shape of the article which said ex-
 posed face of the first layer is intended to
 fit, the exposed face of the second layer be-
 ing shaped to predetermined form. 120

5. A pattern for dental plates comprising
 a layer of easily fusible, plastic material,
 shaped to conform to the roof of the mouth,
 and having an opening therein adapted to
 receive a suction retainer, a second layer 125
 of similar material shaped to conform to
 the first, and having a recess of greater area
 adapted to lie opposite the opening in the

first layer, the bottom of said recess being shaped to parallel in all its contours, the contours of that portion of the roof of the mouth opposite which it is intended to lie, 5 said opening and recess forming an undercut cavity for the reception and securing of a suction retainer.

6. A pattern for a dental plate composed of separable layers, of plastic, easily fusible material, superposed one upon the other, 10 one having an opening therein, and the other a recess opposite and of greater area than said opening, to form an undercut suction retainer cavity within said pattern.

15 7. A pattern for a dental plate composed of separable layers, of plastic, easily fusible material, superposed one upon the other, one having an opening therein, and the other a recess opposite and of greater area 20 than said opening, to form an undercut suc-

tion retainer cavity within said pattern, the bottom of said cavity paralleling in all its contours that portion of the roof of the mouth opposite which it is intended to lie.

8. A pattern for a dental plate composed 25 of separable layers, of plastic, easily fusible material, superposed one upon the other, one having an opening therein, and the other a recess opposite and of greater area 30 than said opening, to form an undercut suction retainer cavity within said pattern, means interposed between said layers, whereby they may be easily separated.

In testimony, I the said JACOB PETRY, have hereunto set my hand.

JACOB PETRY.
